UNITED STATES PATENT OFFICE.

MILES M. GRAY, OF EUREKA SPRINGS, ARKANSAS, ASSIGNOR OF ONE-HALF TO JAMES P. MERRY, OF SAME PLACE.

VEHICLE-WHEEL.

SPECIFICATION forming part of Letters Patent No. 350,929, dated October 19, 1886.

Application filed July 1, 1886. Serial No. 206,847. (Model.)

To all whom it may concern:

Be it known that I, MILES MILLS GRAY, a citizen of the United States, residing at the city of Eureka Springs, county of Carroll, 5 and State of Arkansas, have invented certain new and useful Improvements in Wheels for Wagons, Carriages, and for other Purposes, consisting of an arrangement for tightening or loosening the tire, as desired, at any time 10 to by simply the aid of a wrench, a concise and complete description of which I set forth in the following specification.

In the accompanying drawings, Figure 1 is a perspective side view of a wheel embodying 15 my invention, illustrated at the outer end of the spokes 1, 2, 3, 4, 5, and 6. Fig. 2 is a longitudinal section of the spoke and its attachments. Fig. 3 is a view of the triangular block.

20 My invention consists of a combination of screw attachments, of steel, malleable iron, brass, or other metal, of which *a* illustrates a socket placed upon the end of the spoke, of a square, hexagonal, or oval form on its inner 25 surface, to prevent it from turning upon the spoke. I prefer it differing slightly from the illustration in the drawings by being made larger comparatively with the size of the spoke, and slightly tapering on its inner 30 surface, culminating at the inner end, thereby doing away entirely with the shoulder on the spoke, and inclosing all of the fiber of the wood, thereby giving more strength and durability to the spoke, fitting tightly and resting 35 firmly upon the end of the spoke, being round and straight upon its outer surface, and having a thread cut upon its outer end and principal portion of its length, and left plain at the inner end, at *b*, and fitted with a cap, *C*, having a thread cut in the principal portion of 40 its inner surface, with a flange left blank, as shown at *b'*, to prevent dirt and water from getting into the thread, and all constructed to fit neatly upon the socket *a*, and extending 45 outward and forming the collar *A*, to fit against the felly *B*, and the tenon *d*, to pass into and through the felly or rim, (except as herein-after described,) the tenon being made round and small, according to the strength of the 50 metal of which it is made, and fitted neatly

into a corresponding hole in the felly, thereby giving much more strength and durability to the felly of the same size than the necessarily large wooden tenon of the ordinary spoke. Cap *C* is also formed with a nut, *e*, on its outer 55 surface, of a hexagonal or other convenient form, to fit wrench to turn the entire cap to the right or left—to the right to elongate the spoke and press the felly outward, and thus tighten the tire, or to the left to loosen the 60 same to prevent the injury of the wheel by swelling, should such necessity occur. I make the cap *C* in a single piece entire; but if jarring should prove to loosen it when turned up, and necessity should occur for holding it 65 more firmly to its position, I propose to cut it in two, and thereby form a jam-nut, as at *E*.

To compensate for the expansion of the tire by heat, I introduce a triangular block into one or more of the joints of the felly *D*, with 70 central flange, *f*, the office of which is to act as a dowel, operating in a slot in the ends of the fellies in contact with the block, and side flanges, *g g*, which are constructed heavy at their juncture with the body of the block, and 75 extend with a bevel to an edge to fit a bevel on the corner of the felly to prevent its moving, spreading, or splitting, block *D* having a round hole in the center of its base, and extending through its center to near its apex, 80 into which the tenon of the cap *C* is introduced, so that by turning the cap *C* to the right the triangular block *D* is crowded outward, being less in length than the depth of the felly or rim, and thus forces the joint of the 85 rim asunder, and enlarges the rim to hug and tighten the tire, and all working in unison for the accomplishment of the same results—viz., the tightening or loosening of the tire by simply using a wrench in turning the caps at the 90 ends of the spokes.

I am aware that screw attachments have been used for the expansion of a wheel, and also that wedge-shaped blocks have been introduced into the joints of the felly, but all differing 95 widely from the construction and combination of my invention. Therefore,

Having thus fully set forth and described my invention, its simplicity of mechanical construction rendering it strong and durable 100

and free from the many objections of complicated fixtures, the ease of operating and promptness of securing the object by simply the aid of a wrench, what I claim, and desire 5 to secure by Letters Patent, is—

The combination, in a wheel, of the socket *a*, the cap *C*, having a nut, collar, and tenon, and the flanged triangular metallic block *D*, all op-

erating in unison for the expansion of the wheel by turning the cap *C*, substantially as is set forth.

MILES M. GRAY.
